UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

DISTANCE ROD.

Original application filed May 11, 1927, Serial No. 190,394. Divided and this application filed October 25, 1927. Serial No. 228,549.

In motor vehicles employing chain drives it is necessary to employ means to maintain the distance between the jack shaft and the axle upon which the wheels are mounted in order to maintain the proper distance between the chain sprocket centers. For this purpose distance rods are usually employed. The distance rods which it is proposed to provide according to this invention are novel and are of a nature such as that disclosed in my copending application Serial No. 190,394 filed May 11, 1927, of which this application is a division.

Broadly, the invention contemplates the provision of a distance rod which will effectively maintain the proper distance between chain sprocket centers but which may be readily adjustable. More specifically the invention contemplates the provision of a distance rod so constructed that the adjusting means are relieved of the strains ordinarily impressed thereupon. Accordingly, the rod is made adjustable by the use of a turn buckle screw and the sides of the rod adjacent the screw are serrated and plates formed with teeth are adapted to be clamped thereon in order to maintain the rod in adjustment. In this manner the adjusting screw is relieved of any driving strains which will instead be taken by the plates. The invention further contemplates the provision of novel means for attaching the rod to the jack shaft or the like. These and other objects of the invention will be found fully set forth in the following detailed description which should be read in connection with the accompanying drawings, in which:

Figure 1 is a view of so much of a motor vehicle as is necessary to show a distance rod according to this invention applied thereto;

Figure 2 is a vertical sectional view showing in detail the manner of supporting the end of the distance rod;

Figure 3 is a sectional view taken along the line 3—3 in Figure 2 and looking in the direction of the arrows; and

Figure 4 is a somewhat diagrammatic view illustrating a method of rendering the rod finely adjustable.

Referring to Figure 1, power is transmitted from the flywheel of a motor, for instance, through the transmission shaft *e* to

the jack shaft sections *c'* through differential gearing in the housing *a*, the jack shaft sections being journaled in housings *c'* mounted upon the chassis frame *a*. One end *f'* of the distance rod *f* is rigidly carried with the dead axle *b'* while the other end *f''* is connected to the jack shaft. The end *f''* carries a cylindrical housing *f''* having a cover plate *f''*. The interior of the housing *f''* is formed for the reception of an annular block of yielding non-metallic material *f''* surrounding the housing *c'* in which the jack shaft *c'* is journaled. The jack shaft housing *c'* is hung from the chassis frame through yielding non-metallic material *h* which is carried within a housing *h'*, the housing *h'* being formed with two arms *h''*, which are mounted within the housings *a''* formed on the bracket *a'* by the non-metallic means *a''*.

The end *f''* of the rod is bifurcated as at *f''* and the housing *f''* is formed with similar bifurcated members *f''*. The sides of the bifurcated members are serrated as at *f''* and *f''* for co-operation with serrations *f''* in the plates *f''*. In order to adjust the length of the distance rod the plates are removed, or at least loosened, by unscrewing the studs *f''* and the turn-buckle nut *f''* turned down on the threaded link *f''* to the desired extent, the slots *f''* providing for variations in the distances between the centers of the bolts. The plates *f''* are then clamped down to maintain the rod in adjusted relation. By this means the strains set up on the rod by the driving chain are taken by the plates *f''* instead of by the adjusting means *f''*, *f''*. The adjusting means are thereby relieved of all driving strains.

In order to provide for a very fine degree of adjustment the sides of the bifurcated members *f''* and *f''* may be formed with teeth of different pitch, the co-operating teeth on the plates *f''* being correspondingly formed. Thus, as indicated somewhat diagrammatically in Figure 4, the sides of the bifurcated members *f''* on the housing may be formed with twenty teeth to the inch, while the sides of the bifurcated members *f''* on the rod may be formed with twenty-one teeth to the inch. Then, if the distance between the points of any two given teeth on the plate is one foot, which will also be the distance between the roots of the co-operating teeth on the bi-

- furcated members, and the plate is moved one tooth to the left (in Figure 4) the overall length of the rod will have been shortened an amount equal to the difference between $1' + \frac{1''}{20} - \frac{1''}{21}$ and $1' + \frac{1''}{20} - \frac{1''}{21}$. The rod may be lengthened in corresponding steps by moving it, one tooth at a time, to the right.
- 10 The rod may be lengthened in corresponding steps by moving it, one tooth at a time, to the right.

It will be seen that there has been provided a novel type of adjustable distance rod of such a nature that the adjusting means are relieved from strains ordinarily impressed thereupon and in which a very fine degree of adjustment is possible.

15 A preferred embodiment of the invention has been particularly set forth and described but it is to be understood that no limitation upon the scope of the invention is intended except as indicated in the claims.

What I claim is:

20 1. Means to maintain the proper distance between the centers of chain driven sprockets comprising a distance rod severed in its length, means at the point of severance of the rod to adjust its length, and plates co-operating with the sides of the rod at the point of severance to hold it in adjustable position, whereby the adjusting means are relieved of driving strains.

25 2. A distance rod to maintain the proper distance between the axles of the chain driven sprockets, said distance rod being formed with bifurcated members at one of its ends, a housing carried with one of the axles, said housing being formed with bifurcated members, means between the housing and the distance rod to adjust the length of the distance rod, and plates co-operating with the sides of the bifurcated members on the rod and the housing to maintain the 30 rod in adjusted position, the co-operating sides of the plates and of the bifurcated members being serrated.

35 3. A distance rod to maintain the proper distance between the axles of the chain driven sprockets, said distance rod being formed with bifurcated members at one of its ends, a housing carried with one of the axles, said housing being formed with bifurcated members, means between the housing and the distance rod to adjust the length of the distance rod, and plates co-operating with the sides of the bifurcated members on the rod and the housing to maintain the rod in adjusted position, the sides of the plates 40 and of the bifurcated members on the rod being formed with a series of co-operating teeth and the sides of the plates and the sides of the bifurcated members on the housing being formed with a series of co-operat-

ing teeth of a different pitch than the first 65 named series of teeth.

4. In combination with two axles, sprockets mounted thereon, and a chain operatively engaging the sprockets, an adjustable distance rod operatively interposed between the axles to properly space them, and a plurality of forked arms attached to one of the axles, a support, a corresponding number of housings carried with the support and blocks of yielding non-metallic material 75 within the housings, the ends of the forked arms being seated in said blocks.

5. In combination with two axles, sprockets mounted thereon and a chain operatively engaging the sprockets, an adjustable distance rod operatively interposed between the axles to properly space them, means to mount one of the axles comprising a housing, yielding non-metallic material within the housing in engagement with said housing and said axle, and means to support the housing including a plurality of forked arms attached to the axle, a support, a corresponding number of housings carried with the support and blocks of yielding non-metallic 90 material within the housings, the ends of the forked arms being seated in said blocks.

6. In a motor vehicle, in combination with driving and driven axles, sprockets mounted thereon, and a chain operatively engaging the sprockets, means to maintain the proper distance between the centers of chain driven sprockets comprising a distance rod severed in its length, means at the point of severance of the rod to adjust its length, and plates co-operating with the sides of the rod at the point of severance to hold it in adjustable position, whereby the adjusting means are relieved of driving strains, and means to mount the driving axle comprising a housing and yielding non-metallic material therein, whereby the distance between the sprockets is adjustable.

7. In a motor vehicle having a frame, a driving axle, a driven axle sprung on the frame, sprockets carried by the respective axles, and a chain operatively engaging the sprockets, an adjustable distance rod connected at one end to the driven axle, a housing on the other end of the distance rod surrounding the driving axle, yielding, non-metallic material interposed between said housing and driving axle to form the sole connection therebetween, and means to mount the driving axle on the frame.

8. The combination as claimed in claim 7, wherein the yielding non-metallic material is annular in shape but has cut-away portions to provide for relative motion between the housing and driving axle in every 125 direction.

9. In a motor vehicle having a frame, a driving axle, a driven axle sprung on the

frame, sprockets carried by the respective axles, and a chain operatively engaging the sprockets, an adjustable distance rod connected at one end to the driven axle, a housing on the other end of the distance rod surrounding the driving axle, yielding, non-metallic material interposed between said housing and driving axle to form a connection therebetween, and means to mount the driving axle on the frame comprising yielding, non-metallic material to permit relative motion between said driving axle and frame. 10

This specification signed this 10th day of October A. D., 1927.

ALFRED F. MASURY.
